[57] CLAIM

The ornamental design for an entertainment center, as shown and described.

DESCRIPTION

FIG. 1 is a perspective view of an entertainment center showing my new design;

FIG. 2 is a front elevational view thereof; and,
FIG. 3 is a right side elevational view, the left side being a mirror image thereof.

The books and shelves shown in FIGS. 1 and 2 are part of the surface ornamentation.
The rear surface is flat and unornamented.
